FLUOROMETER

David J. Malk, La Mirada, Calif., assignor to Beckman
Instruments, Inc., a corporation of California

Filed May 10, 1962, Ser. No. 70,068

Term of patent 14 years

(Cl. D16—2)

FIG. 1 is a front perspective view of the fluorometer showing my new design; and

FIG. 2 is a rear perspective view thereof with the cord fragmentarily shown for convenience of illustration.

The side not shown is substantially the same in appearance as the side shown except for the omission of the lever. The stippling on the top of the center panel in FIG. 1 indicates perforations therein and is understood to continue throughout the plain area thereof.

I claim:

The ornamental design for a fluorometer, substantially as shown and described.
